JOURNAL BOX LID

John J. Rulianich, New Kensington, Pa., assignor to Union Spring and Manufacturing Company, New Kensington, Pa., a corporation of Pennsylvania

Application July 22, 1937, Serial No. 154,944

5 Claims. (Cl. 308—47)

This invention relates to the journal boxes of railway rolling stock, and consists in improvements in the structure of the lid of the journal box. The object in view is a lid applicable to and removable from the box with facility and performing its box-closing function efficiently and without chattering.

In the accompanying drawings, Fig. I is a view in front elevation of a lid of the invention, a portion being broken away; Fig. II is a view in side elevation, and in this view the journal box to which the lid is applied is fragmentarily shown; Figs. III, IV, and V are views in front elevation, in plan from beneath, and in side elevation, of a certain supplementary cam block that ordinarily will be included as a part of the lid assembly. Fig. VI is an exploded view of the lid of the invention, viewed in side elevation. Fig. VII is a view, partly in side elevation, partly in medial and longitudinal section, of the assembled lid, ready for application to the journal box. Figs. VIII and IX show, partly in side elevation, partly in medial and longitudinal section, the lid in assembly with the journal box—Fig. VIII showing the lid in open, and Fig. IX showing it in closed position. Figs. X and XI illustrate a modification in details of structure, in which also inventive features are found, Fig. X being a view of the lid in medial and longitudinal section and in assembled position, relatively to a journal box fragmentarily shown in side elevation, and Fig. XI being a view in rear elevation of the lid in detached position, ready to be applied. In the showing of Fig. XI, certain parts are broken away.

The lid of the invention includes, as is usual, a cover plate 1, a spring-retaining hood 2 mounted externally upon the cover plate, and a spring 3 assembled in the pocket formed by and between plate and hood. The assembly of plate, hood, and spring is adapted to be applied as a unit to, and to be pivotally mounted at its upper edge upon, the usual perforated lug 4, cast integrally upon the journal box 5. The lug 4 is here shown to be of conventional and standard form, with cam surfaces 6 and 7, of which surface 6 is a plane surface that is slightly inclined from the horizontal upwardly and outwardly, and surface 7 is a plane surface that is slightly inclined from the vertical downwardly and inwardly. These two cam surfaces define an upward and outward extension of the lug 4, and the angle of the meeting of these surfaces is rounded. This, as has been said, is a feature of standard equipment, and to it the lid of the invention is adaptable. I shall

in the ensuing description characterize this lug as a cam block.

The spring is, in kind, a torsion spring. It includes the coil, to which in Figs. I and VI the reference numeral 3 is immediately applied, and the radially extending arms 8 and 9. The distal end of arm 8 is adapted in the assembly to be anchored at the axis of pivotal turning of the lid, and to such end is formed with a circular terminal loop 10; the arm 9 is adapted through the instrumentality of a roller 11 to bear upon the cam surfaces that are rigidly disposed with relation to the axis of turning. The spring is preferably formed as a double member, with two coils 3, duplicate outer arms 8 and duplicate inner arms 9 that form the two branches of a continuous, U-shaped extension. The coils 3, as shown in Fig. I, arranged symmetrically on opposite sides of the mid-plane of the structure, are inclined slightly, and oppositely inclined, to the horizontal.

The plate 1 is provided with loops 12 at its upper edge, that constitute a knuckle for pivotal mounting, and the hood 2 is provided with perforations 13 in its side walls, and through these in the assembly a pivot-pin 14 passes, to effect the pivotal mounting of the lid upon the perforated cam block 4. The loops 12 and the perforations 13 are elongate, in a direction substantially perpendicular to the plane 15 of the opening of the journal box, to the end that the lid when mounted may accommodate itself to unevennesses and make substantially tight closure around the margins of the opening in the journal box. From the loops 12 upon plate 1 tongues 18 extend, and when assembly has been made these tongues are bent down over the ends of the pivot-pin 14, as shown in Figs. I and II, to retain the pivot-pin in place.

The plate 1 is shaped with a seat 16 upon its outer face, to receive the coils of the spring 3, and hood 2 is shaped to afford a corresponding and co-operating seat 17; and it will be remarked (Figs. II and VII) that in the assembly the coils of the spring are by these portions of the plate 16 and the hood engaged on opposite sides, and held captive between plate and hood. The seat 16 is central in its location upon the plate, to the end that the spring shall exert its tension centrally with respect to the rectangular margin of the opening in the junction box.

The hood 2 is narrower than the plate 1 (cf. Fig. I); it is applied externally upon plate 1; it is united with plate 1 along its vertically extending opposite edges 19, say by means of welded

seams W; and at the upper end the edges of hood and plate stand widely apart, and at the lower end the edge of hood 2 stands away from the surface of the prolonged seat 16. That is to say, 5 the pocket formed by and between plate and hood is open above, to permit of assembly and operation, and is open below at 20 to afford escape of dust and to facilitate cleaning. The hood at its upper end is prolonged, to overarch the contained 10 parts, and at its edge is provided with an in-turned lip 21.

It will presently appear that the spring of my improved lid may be made a very powerful spring—much more powerful than springs ordinarily employed in these structures. And this is 15 a feature of practical value and advantage. Employing such a spring, I find it further advantageous to provide for a large range of spring play, in the movement of the lid between open and closed positions. In accordance with the invention I provide a supplementary cam block, to constitute in the assembly an enlargement of the standard cam block 4, and this supplemental cam block I assemble with the lid, that the whole may 20 be applied as a unit to the journal box with its standard cam block 4. This supplemental cam block is illustrated in detail in Figs. III, IV, and V; it appears in the lid assembly in Fig. VIII, and in the applied position in Figs. II, VIII, and IX. 25 30 It bears the reference numeral 22. This block is provided with perforations 23, and, hollowed beneath, is provided with lugs 24, 25, so that in the assembly it may be secured by the pivot-pin 14 rigidly upon the cam block or pivot-bearing 4. 35 The supplementary cam block 22 is provided with surfaces 26 and 27 that correspond in other respects, when assembly has been made, to the surfaces 6 and 7 of the cam block 4, but, being farther remote from the axis of pivotal turning (as is 40 manifest on considering Figs. VIII and IX), it is at the same time manifest that they serve to effect a wider range of spring play in the opening and closing swing of the assembled lid. The supplementary cam block is provided with cylindrical extensions 28 (in which the perforations for pivotal mounting are co-axially formed) that afford bearing surfaces for the loops 10 upon the spring arms 8. At the rear edge of the cam surface 26 the supplementary cam block is provided 45 with a recess 29, of shape and size to receive the roller 11 upon spring arm 9.

The lid parts so characterized, and shown in Fig. VI in relative positions indicative of assembly, are assembled in the following manner. 50 First, the spring is compressed and the arms 8 and 9 are swung into the crossed relation in which they appear in Fig. VII. Then, the arms 8 of the spring are slightly spread and brought to position upon the cylindrical extensions 28 of the 55 supplementary cam block 22, with the roller at the distal end of the double spring arm urged and held by spring tension against the medial body portion of the cam block. The spring and cam block assembly is then applied to plate 1, 60 with the coils of the spring resting in the seat 16, and the lip 21 of the hood positioned over the roller 11 upon the double spring arm 9. The parts are brought to the positions shown in Fig. VII, and the hood is secured in place, conveniently by means of welded seams W along its edges 19 to the face of plate 1. The spring is 65 preferably made of such strength that its assembly with the cam block exceeds the power of man muscally to effect, but requires rather the power of a press. It is immediately manifest, 70

then, that a lid assembly is effected, in which there is stored by appropriate shop procedure a spring power that may vastly exceed any power that may by any permissible procedure be stored at the time of assembly in the field. In consequence, a relatively great spring tension may be made effective to hold the lid in closed position on the journal box. Furthermore the compression of the turns of the coil, turn upon turn, and the extended engagement of the surfaces of the 10 plate and the hood externally upon the coils present a tremendous frictional resistance to the chattering of the lid when in closed position upon the journal box. 15

The lid assembly is shown in Fig. VII, ready to be applied to a journal box. It will be realized from what has been said that the relatively powerful spring is under tension and that the arms 8 and 9 tend to turn, relatively to the centre of the coil 3, the arm 8 counter-clockwise, the arm 9 clockwise; such turning of the arms is prevented by the engagement of the arms upon the auxiliary cam block 22 interposed between them. The recess 29 in the auxiliary cam block with which the roller 11 makes engagement and the lip 21 on the hood are effective to prevent accidental displacement of the parts. The surface of recess 29 is thus seen to be a supplementary swing-resisting surface. The spring so held by the auxiliary cam block and positioned between plate 1 and hood 2 bears yieldingly through roller 11 upon the inner surface of the hood at lip 21. The lid assembly, so precisely organized in the relative positions of its parts, is precisely in position for application to a journal box in open 30 position with respect thereto. This position of initial application is illustrated in Fig. VIII. When application has been made the pivot-pin 14 is thrust to place, within the perforation of cam block 4, within the perforations 23 of the auxiliary cam block 22, and through the loops 12 of plate 1, and the orifices 13 in hood 2. The lugs 18 of plate 1 are then bent to the position indicated in Fig. I; the pivot-pin is secured in place, and the journal box assembly is complete. 35 The lid then stands in open position, from which position it may be swung (counter-clockwise, Fig. VIII) against the augmented tension of spring 3, until, roller 11 passing beyond the upper surface of the auxiliary cam block, and engaging the outer face of the auxiliary cam block, the tension of the spring becomes effective to carry the swinging lid forward to closed position (Fig. IX) and yieldingly but powerfully to hold it there. 40

And it is manifest that the auxiliary cam block, forming a permanent element of the lid assembly, comprises means for securing the spring under tension, both when the lid structure itself is being assembled, and when the assembled lid structure is being installed on a journal box. 45 And it will be noted that in the ultimate assembly the auxiliary cam block straddles or embraces the cam block on the journal box. 50

In the modification shown in Figs. X and XI, the coils are arranged mid-way in the longitudinal extent of the interior arms of the essentially W-shaped spring 30 (as seen in elevation, Fig. XI), and the loops 31 at the base of the W bear centrally upon the plate 32. Otherwise, the organization is the same; and, as in the form first described, the parts may be so proportioned that the spring is put under great tension in the assembly (that may be made in the shop) of the lid parts; and the lid assembly may be applied as a unit to the box. 55 60 65 70 75 80 85 90 95 100

The journal box opening in this case extends in inclined plane, and plate 32 is counterweighted by extensions 33. When the lid is closed (dotted-line position, Fig. X) these extensions effect a distribution of weight on opposite sides of a vertical plane through the pivotal axis such as to be additionally corrective in the matter of chattering.

As shown in the modified structure, the roller-receiving recess 29 in the supplemental cam block may be omitted. The force of the roller engaging upon the upper surface of the cam block (as shown in Fig. X) is effective to hold the lid in open position. And, in further modification, the rear wall of the supplemental cam block may be extended downward, as at 34, to make contact with the top of the journal box. Thus, in lieu of the lugs 25, above mentioned, the engagement of the cam block with the top of the journal box cooperates with the lug 24 in preventing the rotary displacement of the cam block in the assembled structure.

I claim as my invention:

1. A lid adapted to be pivotally mounted upon a journal box that has a hinge-lug, such lid including a plate, a hood, a spring having two arms tending to move relatively to one another under the tension of the spring, and a cam block, assembled as a unit and adapted to be applied as a unit, the cam block in such assembly, engaged by said arms of the spring, holding the spring under tension in position that characterizes open position with respect to the journal box, the plate of the assembled lid when the lid has been applied being movable pivotally from open position against augmented tension of the said spring, said cam block including passages adapted in the assembly to receive a hinge-pintle, said spring bearing on said block, when the lid is pivotally mounted on said hinge-lug, and being adapted to secure the lid in closed position on the journal box.

2. The structure of the next preceding claim, in which said cam block includes portions adapted to engage said hinge-lug and box in an engagement

preventative of rotation of the block on the axis of said hinge-lug.

3. A cam block adapted for assembly, with a spring-including lid structure, upon the hinge-lug of a journal box; said cam block including a body having spaced-apart cylindrical extensions adapted in assembly to lie on opposite sides of said hinge-lug, said extensions including holes adapted to receive a hinge-pintle extended through said hinge-lug, a portion of said block being adapted to bear on the surface of said hinge-lug, and a cam surface formed on said block, said cam surface and said cylindrical extensions being adapted to cooperate with the spring in said lid structure.

4. A supplementary cam member adapted for assembly with the rigid, perforate, cam block of a journal box equipped with a spring-closed lid, said cam member including two side portions adapted in the assembly to lie severally on opposite sides of said cam block, such side portions severally including passages adapted to receive the hinge-pintle of the box, said cam member including a body portion between said side portions providing an enlargement of the cam surface of the block on which the cam member is assembled, to augment the effect of the spring in said lid.

5. In a lid structure prepared for assembly as a unit upon a journal box, said structure comprising a lid member, a tensioned spring assembled with such lid member, said spring including two arms tending under spring tension to move angularly to one another, and a device cooperating with such arms in securing the spring in tensioned condition; the refinements herein described in which said device consists in a body including a passage for the hinge-pintle of the journal box on which the lid structure is in service assembled, said body being provided with a cam surface engaged by the distal end of one of said spring arms, and being provided with a body portion engaged by the distal end of the other of said spring arms, said body cooperating with said spring arms, when the lid is assembled upon the journal box, in securing the lid structure in closed position on the box.

JOHN J. RULIANCICH.
